MACHINE FOR BENDING FLEXIBLE SHEET MATERIAL

Maurice M. Balsam and Henry M. Balsam, New York, N. Y., assignors to M. M. Balsam, Inc., New York, N. Y.

Application March 19, 1947, Serial No. 735,766

26 Claims. (Cl. 69—8)

1

Our present invention relates to machines for bending flexible sheet material and more particularly to machines for bending flexible sheet material over the corner portions of suit-cases, trunks, boxes and the like.

It is an object of our present invention to provide a machine of the above type which is semi-automatic and can be easily operated without the need of any special skill or experience.

It is another object of our present invention to provide a bending machine for bending leather or similar material which has a great production capacity and is capable of bending the leather with great accuracy.

It is a further object of our present invention to produce a machine of the above type which is very simple in construction and easy to manufacture.

Finally, it is also an object of our present invention to provide a machine of the above type which is easily adjustable to different types of flexible materials.

With the above objects in view our present invention mainly consists of a machine for bending flexible sheet materials over the corner portion of a suit-case or like piece of luggage comprising in combination a plurality of cooperating parts, namely: a machine body, a supporting member mounted on this machine body and adapted to support the corner portion of the suit-case over which the flexible sheet material has to be bent or folded, a pressure means movably mounted on the machine body so as to be adapted to be moved from inoperative position spaced from the above defined supporting member in inclined direction toward this supporting member until said pressure means is in operative position pressing against the supporting member, and operating means adapted to move the above pressure means in inclined direction from inoperative position into operative position, whenever desired.

In accordance with a preferred embodiment of our present invention, the pressure means mentioned above are composed of a pressure member adapted to cooperate with the supporting member and to press against the same so as to bend the flexible sheet material over the corner portion of a suit-case supported by this supporting member and holding means holding the pressure member and being movably attached to the machine body in such a manner as to be adapted to move the pressure member as explained in the preceding paragraph.

We have found it advisable to provide the supporting member with a flat supporting face, preferably with a flat vertical supporting face, and to provide the pressure member with a flat pres-

2

sure face, preferably a flat vertical pressure face adapted to press against the flat vertical supporting face of the supporting member when the pressure member is in operative position. In a machine of this type the holding means holding the pressure member are constructed and arranged so as to hold the pressure member with its flat, preferably vertical pressure face permanently parallel to the flat, preferably vertical supporting face of the supporting member.

The supporting member of a machine of the type proposed by us preferably includes attaching means resiliently attaching the supporting member to the machine body. In order to obtain the necessary pressure, the mentioned attaching means preferably include adjustable spring means so as to hold the supporting member resiliently in the required operative position.

The holding means for the pressure member preferably consist of lever means pivoted at one end to the pressure member holding the same and at the other end to the machine body in such a manner as to be adapted to be turned from inoperative position with the pressure member spaced from the supporting member toward this supporting member until the pressure member is in operative position, pressing against the supporting member.

We have found it advisable to use as lever means a parallelogram-shaped lever system pivoted at one end to the pressure member holding the same with its vertical pressure face permanently in vertical position and at the other end to the machine body in such a manner as to be adapted to be turned between inoperative and operative position as explained above.

In order to properly hold the corner portion of the suit-case during bending of the leather sheet over the same, it is advisable to provide the supporting member with a supporting face, combined of a curved supporting face portion and a flat supporting face portion, and to provide the pressure member with a pressure face combined of a curved pressure face portion and a flat pressure face portion adapted to cooperate with the corresponding supporting face portions of the supporting member as will be described farther below in detail.

The novel features which we consider as characteristic for our invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a cross section through a bending machine according to our present invention in operative position, along line 1—1 of Fig. 4;

Fig. 2 is a side view of the upper part of the machine shown in Fig. 1 in inoperative position, seen in direction of arrow 2 of Fig. 4;

Fig. 3 is a top view of the machine shown in Figs. 1 and 2, seen in direction of arrow 3 of Fig. 1; and

Fig. 4 is a front view of the machine shown in Figs. 1 to 3, with part of the supporting means broken off, seen in direction of arrow 4 of Fig. 1.

The bending machine, according to our present invention comprises as main elements, a machine body or frame 10 on which the supporting arrangement 11 and the bending arrangement 12 are mounted as will be described farther below in detail.

The supporting arrangement 11 serving for supporting the corner portion of the suit-case over which the leather sheet is bent consists of an arm 13 resiliently mounted at its bottom end 14 by means of the transversely extending support 15 to the machine body 10, and the supporting member 16 firmly secured to arm 13 at the upper end 17 thereof. The resilient mounting of the arm 13 at its bottom end 14 to the machine body 10 enables pivoting of the arm to a very slight degree about the support 15 in direction of arrow 18. The arm 13 is pressed into operative position against direction of arrow 18 and held in this position as shown in Figure 1 by means of the spring arrangement 19. This spring arrangement includes a transversal support 20 secured to the machine body 10, a screw 21 screwed into the screw hole 22 in this support, and a spring 23 arranged between the head of the screw 21 and the front face 24 of arm 13, permanently forcing the same in direction of arrow 25.

The supporting member 16 is mounted at the upper end of arm 13 by means of the holding plate 26 screwed as clearly shown in Fig. 4 by means of screws 27 to the upper end 17 of the arm 13, and by screws 28 to the supporting member 16.

As clearly shown in Figs. 1 and 4, the supporting member 16 is provided with a flat vertical supporting face 29 and a curve supporting face 30.

The bending arrangement 12 mentioned above includes a parallelogram-shaped lever system consisting of the four lever members 31, 32, 33 and 34 respectively. These lever members are pivoted at their rear ends by means of the pivot pins 35 and 36 to the vertically extending projecting walls 37 and 38 mounted by means of screws 39 to the top face 40 of the machine body 10. The lever arms 31 to 34 are turnable about the pivot pins 35 and 36 from the inoperative position shown in Fig. 2 into the operative position shown in Fig. 1 and back, as will be described farther below in detail.

The pressure member 41 is pivotally attached to the lever members 31, 32, 33 and 34 by means of the screws 42, 43, 44 and 44' respectively. Proper spacing of the lever members at their rear ends is obtained by the spacing sleeves 45.

The pressure member 41 consists of two member portions, namely: the curved pressure member portion 46 provided with the curved pressure face 47 and the flat pressure member portion 48 provided with the flat vertical pressure face 49. It is evident from the drawings, particularly Figs. 1 and 2 thereof, that the vertical pressure face 49 of the pressure member 41 will always stay in

vertical position, i. e. it will be parallel to the supporting face 29 of the supporting member 16 while the pressure member is in operative position shown in Fig. 1, as well as while it is in inoperative position shown in Fig. 2 as well as during movement of the pressure member from one of these positions into the other. The two pressure member portions 46 and 48 are permanently secured to each other by means of the screws 50.

We wish to note that as clearly shown in the drawings, particularly Fig. 4 thereof, the curvature of the curved supporting face 30 of the supporting member 16 is identical with the curvature of the curved pressure face 47 of the pressure member portion 46. Furthermore, we wish also to stress that the flat pressure member portion 48 of the pressure member 41 is provided at its lower edge 51 with a substantially semi-circular cut-out having also substantially the same curvature as the curved pressure face 47 of the pressure member 41 and the curved supporting face 30 of the supporting member 16. The provision of this cut-out is important as it serves for proper gripping and bending of the flexible sheet during operation of the machine. In order to enhance the bending effect it is advisable in some cases to provide on the inner face of the flat pressure member portion 48 vertical grooves 52 indicated in Fig. 4 in dotted lines.

In order to move the parallelogram-shaped lever system together with the pressure member 41 from the inoperative position shown in Fig. 2 into the operative position shown in Fig. 1, we provide the operating lever arrangement 53 consisting of the four levers 54, 55, 56 and 57 respectively. The levers 55 and 54 are pivoted at their front ends by means of pivot pin 58 to the lower lever members 32 and 33 and at their rear ends by means of the pivot pin 59 to the levers 56 and 57; these levers 56 and 57 in turn are pivoted at their rear ends by the pivot pin 35 to the upper lever members 31 and 34. The pivot sleeve 60 surrounding the pivot pin 59 is extended downward and provided with a screw threaded hole 61 into which the upper screw threaded end of rod 62 is screwed. This rod 62 is operatively connected at its lower end with the pedal lever 63. This pedal lever in turn is pivoted at one end in well known manner to the machine body 10 and carries at its other end the pedal 64. Spring 65 secured at one end to the pedal lever 63 and at its other end to the body 10 permanently tends to move the pedal lever 63 together with the pedal 64 upward in direction of arrow 66 keeping thereby the entire bending arrangement 12 in inoperative position shown in Fig. 2.

Our new bending machine operates as follows:

The machine is used as set forth above mainly for folding leather sheets, e. g. leather strips over the corner portions of suit cases. Such suit cases as well known, are usually composed of two parts, namely a suit case bottom and a suit case top. Each of these parts in turn consists of a top or bottom wall, and four relatively narrow side walls arranged in well known manner.

Such suit cases are usually provided along the edges of two opposite side walls with relatively narrow leather strips and it is the purpose of our new bending machine to enable folding of these leather strips over the corners of these side walls.

Before bending the leather strip to be folded over the edges and corners of a particular side wall of the suit case it is secured to the edge portions of the adjacent cover wall and side wall so as to project beyond the same. After such

preparation the leather strip is ready for bending by our new machine.

For this purpose the machine is moved into its inoperative position shown in Figure 2. While the machine is in this position, the corner portion of the suit case over which the leather strip is to be folded is placed on the supporting member 16 in such a manner that the inner surface of the side wall over which the strip is to be folded is superimposed upon the flat supporting face 29 of the supporting member and the adjacent edge portions of the cover wall and of the adjacent side wall are superimposed upon the curved supporting face 30 of this member.

After the suit-case is in proper position, the operator steps on pedal 64, turning thereby the bending arrangement 12 together with pressure member 41 from its inoperative position shown in Fig. 2 into its operative position shown in Fig. 1. During such turning the front edge 51 of the pressure member 41 engages the projecting leather sheet and turns the same slowly downward until it is superimposed upon the outer surface of the side wall over which the leather strip is bent against the same by the flat pressure face 49 of the pressure member 41.

After proper bending of the leather sheet, the pedal 64 is released and the bending arrangement 12 automatically returns by action of spring 65 into its inoperative position shown in Fig. 2.

It will be understood that each of the elements described above, or two or more together, may also find a useful application in other types of bending machines differing from the types described above.

While we have illustrated and described the invention as embodied in bending machines for bending leather sheets over the corners of suit-cases and like pieces of luggage, we do not intend to be limited to the details shown, since various modifications and structural changes may be made without departing in any way from the spirit of our invention.

Without further analysis, the foregoing will so fully reveal the gist of our invention that others can by applying current knowledge readily adapt it for various applications without omitting features that, from the standpoint of prior art, fairly constitute essential characteristics of the generic or specific aspects of this invention and therefore, such adaptations should and are intended to be comprehended within the meaning and range of equivalence of the following claims.

What we claim as new and desire to secure by Letters Patent is:

1. A machine for bending flexible sheet material over the corner portion of a suit-case or the like comprising in combination a machine body; a supporting member mounted on said machine body and adapted to support said corner portion of the suit-case; a pressure means movably mounted on said machine body so as to be adapted to be moved from inoperative position spaced from said supporting member in inclined direction toward this supporting member until said pressure means is in operative position pressing against said supporting member; and operating means adapted to move said pressure means in inclined direction from inoperative position into operative position, whenever desired.

2. A machine for bending flexible sheet material over the corner portion of a suit-case or the like comprising in combination a machine body; a supporting member mounted on said

machine body and adapted to support said corner portion of the suit-case; a pressure member adapted to cooperate with said supporting member and to press against the same so as to bend said flexible sheet material over the corner portion of a suit-case supported by said supporting member; holding means holding said pressure member and being movably attached to said machine body in such a manner as to be adapted to be moved from inoperative position with said pressure member spaced from said supporting member in inclined direction toward this supporting member until said pressure member is in operative position pressing against said supporting member; and operating means adapted to move said holding means together with said pressure member in inclined direction from inoperative into operative position, whenever desired.

3. A machine for bending flexible sheet material over the corner portion of a suit-case or the like comprising in combination a machine body; a supporting member having a vertical supporting face and mounted on said machine body so as to be adapted to support said corner portion of the suit-case; a pressure member having a vertical pressure face adapted to cooperate with said supporting member and to press with said vertical pressure face against said vertical supporting face of said supporting member so as to bend said flexible sheet material over the corner portion of a suit-case supported by said supporting member; holding means holding said pressure member with its vertical pressure face parallel to said vertical supporting face of said supporting member, said holding means being movably attached to said machine body in such a manner as to be adapted to be moved from inoperative position with said pressure member spaced from said supporting member in inclined direction toward this supporting member until said pressure member is in operative position pressing with its vertical pressure face against the vertical supporting face of said supporting member; and operating means adapted to move said holding means together with said pressure member in inclined direction from inoperative into operative position, whenever desired.

4. A machine for bending flexible sheet material over the corner portion of a suit-case or the like comprising in combination a machine body; a supporting member having a flat supporting face and mounted on said machine body so as to be adapted to support said corner portion of the suit-case; a pressure member having a flat pressure face adapted to cooperate with said supporting member and to press with said flat pressure face against said flat supporting face of said supporting member so as to bend said flexible sheet material over the corner portion of a suit-case supported by said supporting member; holding means holding said pressure member with its flat pressure face parallel to said flat supporting face of said supporting member, said holding means being movably attached to said machine body in such a manner as to be adapted to be moved from inoperative position with said pressure member spaced from said supporting member in inclined direction toward this supporting member until said pressure member is in operative position pressing with its flat pressure face against the flat supporting face of said supporting member; and operating means adapted to move said holding means together with said pressure member in inclined direction toward this supporting member until said pressure member is in operative position pressing with its flat pressure face against the flat supporting face of said supporting member; and operating means

with said pressure member in inclined direction from inoperative into operative position, whenever desired.

5. A machine for bending flexible sheet material over the corner portion of a suit-case or the like comprising in combination a machine body; a supporting member having a vertical supporting face and being shaped so as to be adapted to support said corner portion of the suit-case; securing means resiliently securing said supporting member to said machine body; a pressure member having a vertical pressure face adapted to cooperate with said supporting member and to press with said vertical pressure face against said vertical supporting face of said supporting member so as to bend said flexible sheet material over the corner portion of a suit-case supported by said supporting member; holding means holding said pressure member with its vertical pressure face parallel to said vertical supporting face of said supporting member, said holding means being movably attached to said machine body in such a manner as to be adapted to be moved from inoperative position with said pressure member spaced from said supporting member in inclined direction toward this supporting member until said pressure member is in operative position pressing with its vertical pressure face against the vertical supporting face of said supporting member; and operating means adapted to move said holding means together with said pressure member in inclined direction from inoperative into operative position, whenever desired.

6. A machine for bending flexible sheet material over the corner portion of a suit-case or the like comprising in combination a machine body; a supporting member having a vertical supporting face and being shaped so as to be adapted to support said corner portion of the suit-case; a holding member movably securing said supporting member to said machine body; adjustable spring means combined with said holding member so as to resiliently hold the same together with said supporting member in the required operative position; a pressure member having a vertical pressure face adapted to cooperate with said supporting member and to press with said vertical pressure face against said vertical supporting face of said supporting member so as to bend said flexible sheet material over the corner portion of a suit-case supported by said supporting member; holding means holding said pressure member with its vertical pressure face parallel to said vertical supporting face of said supporting member, said holding means being movably attached to said machine body in such a manner as to be adapted to be moved from inoperative position with said pressure member spaced from said supporting member in inclined direction toward this supporting member until said pressure member is in operative position pressing with its vertical pressure face against the vertical supporting face of said supporting member; and operating means adapted to move said holding means together with said pressure member in inclined direction from inoperative into operative position, whenever desired.

7. A machine for bending flexible sheet material over the corner portion of a suit-case or the like comprising in combination a machine body; a supporting member mounted on said machine body and adapted to support said corner portion of the suit-case; a pressure member adapted to

cooperate with said supporting member and to press against the same so as to bend said flexible sheet material over the corner portion of a suit-case supported by said supporting member; lever means pivoted at one end to said pressure member holding the same and at the other end to said machine body in such a manner as to be adapted to be turned from inoperative position with said pressure member spaced from said supporting member toward this supporting member until said pressure member is in operative position pressing against said supporting member; and operating means adapted to turn said lever means about its pivoting point together with said pressure member from inoperative into operative position, whenever desired.

8. A machine for bending flexible sheet material over the corner portion of a suit-case or the like comprising in combination a machine body; a supporting member having a vertical supporting face and mounted on said machine body so as to be adapted to support said corner portion of the suit-case; a pressure member having a vertical pressure face adapted to cooperate with said supporting member and to press with said vertical pressure face against said vertical supporting face of said supporting member so as to bend said flexible sheet material over the corner portion of a suit-case supported by said supporting member; lever means pivoted at one end to said pressure member holding the same with said vertical pressure face permanently in vertical position and at the other end to said machine body in such a manner as to be adapted to be turned from inoperative position with said vertical pressure face of said pressure member spaced from said vertical supporting face of said supporting member toward said supporting member until said pressure member is in operative position pressing with said vertical pressure face against the vertical pressure face of said supporting member; and operating means combined with said lever means and adapted to turn the same about its pivoting point together with said pressure member from inoperative into operative position, whenever desired.

9. A machine for bending flexible sheet material over the corner portion of a suit-case or the like comprising in combination a machine body; a supporting member having a flat supporting face and mounted on said machine body so as to be adapted to support said corner portion of the suit-case; a pressure member having a flat pressure face adapted to cooperate with said supporting member and to press with said flat pressure face against said flat supporting face of said supporting member so as to bend said flexible sheet material over the corner portion of a suit-case supported by said supporting member; lever means pivoted at one end to said pressure member holding the same with said flat pressure face permanently parallel to said flat supporting face of said supporting member and at the other end to said machine body in such a manner as to be adapted to be turned from inoperative position with said flat pressure face of said pressure member spaced from said flat supporting face of said supporting member toward said supporting member until said pressure member is in operative position pressing with said flat pressure face against the flat pressure face of said supporting member; and operating means combined with said lever means and adapted to turn the same about its pivoting point together with said pressure

member from inoperative into operative position, whenever desired.

10. A machine for bending flexible sheet material over the corner portion of a suit-case or the like comprising in combination a machine body; a supporting member having a vertical supporting face and mounted on said machine body so as to be adapted to support said corner portion of the suit-case; a pressure member having a vertical pressure face adapted to cooperate with said supporting member and to press with said vertical pressure face against said vertical supporting face of said supporting member so as to bend said flexible sheet material over the corner portion of a suit-case supported by said supporting member; a parallelogram-shaped lever system pivoted at one end to said pressure member holding the same with said vertical pressure face permanently in vertical position and at the other end to said machine body in such a manner as to be adapted to be turned from inoperative position with said vertical pressure face of said pressure member spaced from said vertical supporting face of said supporting member toward said supporting member until said pressure member is in operative position pressing with said vertical pressure face against the vertical pressure face of said supporting member; and operating means combined with said parallelogram-shaped lever system and adapted to turn the same about its pivoting point together with said pressure member from inoperative into operative position, whenever desired.

11. A machine for bending flexible sheet material over the corner portion of a suit-case or the like comprising in combination a machine body; a supporting member having a flat supporting face and mounted on said machine body so as to be adapted to support said corner portion of the suit-case; a pressure member having a flat pressure face adapted to cooperate with said supporting member and to press with said flat pressure face against said flat supporting face of said supporting member so as to bend said flexible sheet material over the corner portion of a suit-case supported by said supporting member; a parallelogram-shaped lever system pivoted at one end to said pressure member holding the same with said flat pressure face permanently parallel to said flat supporting face of said supporting member and at the other end to said machine body in such a manner as to be adapted to be turned from inoperative position with said flat pressure face of said pressure member spaced from said flat supporting face of said supporting member toward said supporting member until said pressure member is in operative position pressing with said flat pressure face against the flat pressure face of said supporting member; and operating means combined with said parallelogram-shaped lever system and adapted to turn the same about its pivoting point together with said pressure member from inoperative into operative position, whenever desired.

12. A machine for bending flexible sheet material over the corner portion of a suit-case or the like comprising in combination a machine body; a supporting member having a vertical supporting face and mounted on said machine body so as to be adapted to support said corner portion of the suit-case; a pressure member having a vertical pressure face adapted to cooperate with said supporting member and to press with said vertical pressure face against said vertical supporting face of said supporting member so as to bend said flexible sheet material over the corner portion of a suit-case supported by

a suit-case supported by said supporting member; a parallelogram-shaped lever system; first horizontal pivoting means pivotally attaching said pressure member to said parallelogram-shaped lever system at one end thereof with said vertical pressure face of said pressure member permanently in vertical position; second horizontal pivoting means pivotally attaching said parallelogram-shaped lever system at its other end to said machine body in such a manner that said parallelogram-shaped lever system is adapted to be turned about said second horizontal pivoting means from inoperative position with said vertical pressure face of said pressure member spaced from said vertical supporting face of said supporting member toward said supporting member until said pressure member is in operative position pressing with said vertical pressure face against the vertical pressure face of said supporting member; and operating means combined with said parallelogram-shaped lever system and adapted to turn the same about its pivoting point together with said pressure member from inoperative into operative position, whenever desired.

13. A machine for bending flexible sheet material over the corner portion of a suit-case or the like comprising in combination a machine body; a supporting member having a vertical supporting face and being shaped so as to be adapted to support said corner portion of the suit-case; securing means resiliently securing said supporting member to said machine body; a pressure member having a vertical pressure face adapted to cooperate with said supporting member and to press with said vertical pressure face against said vertical supporting face of said supporting member so as to bend said flexible sheet material over the corner portion of a suit-case supported by said supporting member; lever means pivoted at one end to said pressure member holding the same with said pressure face permanently in vertical position and at the other end to said machine body in such a manner as to be adapted to be turned from inoperative position with said vertical pressure face of said pressure member spaced from said vertical supporting face of said supporting member toward said supporting member until said pressure member is in operative position pressing with said vertical pressure face against the vertical pressure face of said supporting member; and operating means combined with said lever means and adapted to turn the same about its pivoting point together with said pressure member from inoperative into operative position, whenever desired.

14. A machine for bending flexible sheet material over the corner portion of a suit-case or the like comprising in combination a machine body; a supporting member having a vertical supporting face and being shaped so as to be adapted to support said corner portion of the suit-case; a holding member resiliently attaching said supporting member to said machine body; adjustable spring means combined with said holding member so as to resiliently hold the same together with said supporting member in the required operative position; a pressure member having a vertical pressure face adapted to cooperate with said supporting member and to press with said vertical pressure face against said vertical supporting face of said supporting member so as to bend said flexible sheet material over the corner portion of a suit-case supported by said supporting member; lever means pivoted at one end to said pressure member holding the

same with said vertical pressure face permanently in vertical position and at the other end to said machine body in such a manner as to be adapted to be turned from inoperative position with said vertical pressure face of said pressure member spaced from said vertical supporting face of said supporting member toward said supporting member until said pressure member is in operative position pressing with said vertical pressure face against the vertical pressure face of said supporting member; and operating means combined with said lever means and adapted to turn the same about its pivoting point together with said pressure member from inoperative into operative position, whenever desired.

15. A machine for bending flexible sheet material over the corner portion of a suit-case or the like comprising in combination a machine body; a supporting member having a flat supporting face and being shaped so as to be adapted to support said corner portion of the suit-case; securing means resiliently attaching said supporting member to said machine body; a pressure member having a flat pressure face adapted to cooperate with said supporting member and to press with said flat pressure face against said flat supporting face of said supporting member so as to bend said flexible sheet material over the corner portion of a suit-case supported by said supporting member; lever means pivoted at one end to said pressure member holding the same with said flat pressure face permanently parallel to said flat supporting face of said supporting member and at the other end to said machine body in such a manner as to be adapted to be turned from inoperative position with said flat pressure face of said pressure member spaced from said flat supporting face of said supporting member toward said supporting member until said pressure member is in operative position pressing with said flat pressure face against the flat pressure face of said supporting member; and operating means combined with said lever means and adapted to turn the same about its pivoting point together with said pressure member from inoperative into operative position, whenever desired.

16. A machine for bending flexible sheet material over the corner portion of a suit-case or the like comprising in combination a machine body; a supporting member having a vertical supporting face and being shaped so as to be adapted to support said corner portion of the suit-case; a holding member resiliently attaching said supporting member to said machine body; adjustable spring means combined with said holding member so as to resiliently hold the same together with said supporting member in the required operative position; a pressure member having a vertical pressure face adapted to cooperate with said supporting member and to press with said vertical pressure face against said vertical supporting face of said supporting member so as to bend said flexible sheet material over the corner portion of a suit-case supported by said supporting member; a parallelogram-shaped lever system pivoted at one end to said pressure member holding the same with said vertical pressure face permanently in vertical position and at the other end to said machine body in such a manner as to be adapted to be turned from inoperative position with said vertical pressure face of said pressure member spaced from said vertical supporting face of said supporting member toward said supporting member until said pressure member is in operative

position pressing with said vertical pressure face against the vertical pressure face of said supporting member; and operating means combined with said parallelogram-shaped lever system and adapted to turn the same about its pivoting point together with said pressure member from inoperative into operative position, whenever desired.

17. A machine for bending flexible sheet material over the corner portion of a suit-case or the like comprising in combination a machine body; a supporting member having a flat supporting face and being shaped so as to be adapted to support said corner portion of the suit-case; securing means resiliently attaching said supporting member to said machine body; a pressure member having a flat pressure face adapted to cooperate with said supporting member and to press with said flat pressure face against said flat supporting face of said supporting member so as to bend said flexible sheet material over the corner portion of a suit-case supported by said supporting member; a parallelogram-shaped lever system pivoted at one end to said pressure member holding the same with said flat pressure face of said flat pressure face permanently parallel to said flat supporting face of said supporting member and at the other end to said machine body in such a manner as to be adapted to be turned from inoperative position with said flat pressure face of said pressure member spaced from said flat supporting face of said supporting member toward said supporting member until said pressure member is in operative position pressing with said flat pressure face against the flat pressure face of said supporting member; and operating means combined with said parallelogram-shaped lever system and adapted to turn the same about its pivoting point together with said pressure member from inoperative into operative position, whenever desired.

18. A machine for bending flexible sheet material over the corner portion of a suit-case or the like comprising in combination a machine body; a supporting member having a vertical supporting face and being shaped so as to be adapted to support said corner portion of the suit-case; a holding member resiliently attaching said supporting member to said machine body; adjustable spring means combined with said holding member so as to resiliently hold the same together with said supporting member in the required operative position; a pressure member having a vertical pressure face adapted to cooperate with said supporting member and to press with said vertical pressure face against said vertical supporting face of said supporting member so as to bend said flexible sheet material over the corner portion of a suit-case supported by said supporting member; a parallelogram-shaped lever system; first horizontal pivoting means pivotally attaching said pressure member to said parallelogram-shaped lever system at one end thereof with said vertical pressure face of said pressure member permanently in vertical position; second horizontal pivoting means pivotally attaching said parallelogram-shaped lever system at its other end to said machine body in such a manner that said parallelogram-shaped lever system is adapted to be turned about said second horizontal pivoting means from inoperative position with said vertical pressure face of said pressure member spaced from said vertical supporting face of said supporting member toward said supporting member until said pressure member is in operative position pressing with said vertical pressure face against the vertical pressure face

of said supporting member; and operating means combined with said parallelogram-shaped lever system and adapted to turn the same about its pivoting point together with said pressure member from inoperative into operative position, whenever desired.

19. A machine for bending flexible sheet material over the corner portion of a suit-case or the like comprising in combination a machine body; a supporting member having a supporting face combined of a curved supporting face portion and a flat vertical supporting face portion, said supporting member mounted on said machine body so as to be adapted to support said corner portion of the suit-case; a pressure member having a pressure face combined of a curved pressure face portion and a flat vertical pressure face portion, said pressure member adapted to cooperate with said supporting member and adapted to press simultaneously with said curved pressure face portion against said curved supporting face portion and said flat vertical pressure face portion against said flat vertical supporting face portion of said supporting member so as to bend said flexible sheet material over the corner portion of a suit-case supported by said supporting member; holding means holding said pressure member permanently with its curved pressure face portion parallel to said curved supporting face portion and its flat vertical pressure face portion parallel to said flat vertical supporting face portion of said supporting member, said holding means being movably attached to said machine body in such a manner as to be adapted to be moved from inoperative position with said pressure member spaced from said supporting member in inclined direction toward this supporting member until said pressure member is in operative position pressing with its pressure face portions against the corresponding supporting face portions of said supporting member; and operating means adapted to move said holding means together with said pressure member in inclined direction from inoperative into operative position, whenever desired.

20. A machine for bending flexible sheet material over the corner portion of a suit-case or the like comprising in combination a machine body; a supporting member having a supporting face combined of a curved supporting face portion and a flat vertical supporting face portion; a holding member resiliently attaching said supporting member to said machine body; adjustable spring means combined with said holding member so as to resiliently hold the same together with said supporting member in the required operative position; a pressure member having a pressure face combined of a curved pressure face portion and a flat vertical pressure face portion, said pressure member adapted to cooperate with said supporting member and adapted to press simultaneously with said curved pressure face portion against said curved pressure face portion and said flat vertical pressure face portion against said flat vertical supporting face portion of said supporting member so as to bend said flexible sheet material over the corner portion of a suit-case supported by said supporting member; a parallelogram-shaped lever system; first horizontal pivoting means pivotally attaching said pressure member to said parallelogram-shaped lever system at one end thereof with said flat vertical pressure face portion of said pressure member permanently in vertical position; second horizontal pivoting means pivotally attaching said parallelogram-

shaped lever system at its other end to said machine body in such a manner that said parallelogram-shaped lever system is adapted to be turned from inoperative position with its curved pressure face portion spaced from said curved supporting face portion and flat vertical pressure face portion spaced from said flat vertical supporting face portion of said supporting member toward said supporting member until said pressure member is in operative position pressing with its curved pressure face portion against said curved supporting face portion and its flat vertical pressure face portion against said flat vertical supporting face portion of said supporting member; and operating means combined with said parallelogram-shaped lever system and adapted to turn the same about its pivoting point together with said pressure member from inoperative into operative position, whenever desired.

20 21. In a machine of the type claimed in claim 1, said supporting member having an arcuate supporting face forming part of a cylindrical surface and a flat supporting face being normal to the axis of said cylindrical surface, and said pressure means being composed of an arcuate pressure member provided with an arcuate pressure face having the same curvature as said arcuate supporting face of said supporting member and adapted to cooperate with and press against the same and of a projecting flat pressure plate having a flat pressure face adapted to cooperate with and press against said flat supporting face of said supporting member.

25 22. In a machine of the type claimed in claim 21, said pressure plate having a straight bending edge and an arcuate cut-out in said straight bending edge.

30 23. In a machine of the type claimed in claim 22, said arcuate cut-out in said straight bending edge of said pressure plate having a curvature being substantially equal to the curvature of said arcuate pressure face of said arcuate pressure member and of said arcuate supporting face of said supporting member.

35 24. In a machine for bending flexible sheet material of the type claimed in claim 1, said supporting member having a vertical flat supporting face and an arcuate supporting face forming part of a cylindrical surface having a horizontal axis, and 40 said pressure means being composed of an arcuate pressure member having an arcuate pressure face forming part of a cylindrical surface having a horizontal axis and having the same curvature as said arcuate supporting face of said supporting member and adapted to cooperate with and press against the same and of a downwardly projecting vertical flat pressure plate having a vertical flat pressure face adapted to cooperate with and press against said vertical flat supporting face of said supporting member.

45 25. In a machine of the type claimed in claim 24, said pressure plate having a horizontal bending edge and a substantially semi-circular cut-out having rounded corners in said horizontal straight bending edge.

50 26. In a machine of the type claimed in claim 25, said arcuate cut-out in said horizontal straight bending edge of said downwardly projecting vertical flat pressure plate having a curvature being substantially equal to the curvature of said arcuate pressure face of said arcuate pressure member and of said arcuate supporting face of said supporting member.
